UNITED STATES PATENT OFFICE.

ALBERT F. HILLENBEITEL, OF CHICAGO, ILLINOIS, ASSIGNOR TO WILSON-WESTERN SPORTING GOODS COMPANY, OF CHICAGO, ILLINOIS, A CORPORATION OF DELAWARE.

BASEBALL GLOVE.

Application filed September 4, 1926. Serial No. 133,530.

My invention relates to gloves such as are used in playing baseball, and is particularly concerned with the provision of novel conformation and structure for that type of 5 gloves usually worn by players in the out field and on the bases.

Among the salient features of my invention are:

First. The provision of a glove having 10 greatly increased durability and greatly prolonged life.

Second. The accomplishment of the foregoing result by the provision of a glove having certain external finger pockets integrally joined.

Third. The provision of the foregoing features and others without affecting disadvantageously the fit or feel of the glove on the hand of the player.

Fourth. The provision of a glove having a novel catching area comprising the area of leather between the first and second fingers, made by a shortened split between these fingers, together with connecting 25 means between the thumb and forefinger, giving a glove in which the point of catch is located farther toward the ends of the fingers, resulting in more flexible impact resisting means without possibility of a fumble through the fingers or injuring the first two fingers of the player by splitting or straining the latter too far apart.

Fifth. The provision of a glove having 30 all the combined advantages of a light mitt and fielder's glove.

Other objects of my invention will appear from the following description and the accompanying drawings, in which similar characters and references indicate similar 35 parts throughout the several views.

In the drawings,

Figure 1 is a view showing the palm and catching surface of my improved glove;

Figure 2 is a view of my novel baseball 45 glove, partially broken away showing cross section of the finger pockets and the finger pocket covers with the fingers disposed therein.

The baseball glove shown in Fig. 1 comprises the usual pad or cushioning means 50 (not shown), which is enclosed in a suitable leather case or covering. This covering comprises a plurality of sheets or pieces of leather, of which 10 indicates the outer

palm covering, an integral piece of leather 55 including portions for each outer finger covering 25, 27, 29 and 11, and also the rear portions of the forefinger 25 and the little finger 11.

Referring to Figure 1, it will be noted that the outer casing of the little finger is formed by folding the right end of this piece of leather back upon itself and stitching the abutting edges of the outer little finger casing together, down as far as the 60 palm piece is split.

The first finger casing may also be formed by folding back the end of the palm piece about this finger, but as distinguished from the little finger, it will be observed from Figures 1 and 2 that the abutting edges of that part of the palm piece forming this finger are only stitched together down to the point 19. From this point the remainder of the edge of the first finger casing is joined to the back piece 31 (Figure 2) and the remaining edge of the back piece 31 is joined to the edge of the second finger portion of the palm piece around the end of the second finger to the point 18 where the split in the palm piece between the second and third fingers terminates.

From the point 18, the back piece 31 is joined to the back piece 32, as will be seen in Figure 2, and the remainder of the back piece 32 is joined at its edge to the third finger portion of the palm piece around the end of the third finger casing to the point 23. From the point 23 the back piece 32 is joined to the flap 33 of the little finger casing, which flap is integral with the palm piece. As has been previously described, the remainder of the edges of the little finger portion of the palm piece are joined together to form the little finger portion.

It will thus be observed that the first and second fingers are enclosed in the same outer casing from the palm up to a certain point 19, after which the said outer casing is divided to form two outer casings for the 100 ends of the first two fingers. The second and third fingers are likewise enclosed in the same outer casing up to a certain point 18, from which the separate outer finger casings extend.

The outstanding characteristic of this palm covering is the fact that the first two fingers are not split all the distance down

- between the said fingers and the palm, but are joined by an integral piece of leather up to a point 19 between said fingers, being split from there on to the end of the fingers.
- 6 In a similar manner the second and third outer finger coverings 27—29 may be split a distance exceeding somewhat the split between the first two fingers, but not yet extending the whole distance down to the palm. This arrangement may be varied, and the first two fingers may be joined entirely, an integral piece of leather covering their forward surfaces, but I prefer to split these fingers substantially half the distance between the tips of the fingers and the palm, and likewise to split the second and third fingers of the glove to a distance 18 substantially two-thirds or three-fourths the distance from the finger tips to the palm for a purpose further to be described. It will be noted that the split between the outer coverings 29, 11 of the third and little fingers is made extending substantially all the distance down to the palm, in the usual manner of construction of gloves of this type.
- In order that the glove may have the same feel on the hand of the player, and in order to make the glove fit upon his hand without slipping, I provide an inner lining of the usual type, having finger pockets, 26, 28, 30 and 12 separated from each other, and having partitions extending all the way down between the fingers to points 16, 17 and 24. The space between the respective outer and inner linings is filled with cushioning means disposed to protect the hand of the wearer, particularly at the point of impact where the ball is caught, the disposition of the cushioning means in the present case being practically the same except that here it is extended to also protect the hand above the joined space of the finger pockets 25 and 27. The thumb pocket 21 with its lining and cushioning means is constructed in a manner well known to those skilled in the art.
- In order to join the outer thumb casing 21 and the outer forefinger casing 25 to form a better catching surface, I provide an adjustable connecting means 22 for connecting said casings which may be made of any flat, flexible wear-resisting material, but which is preferably constructed as described in co-pending application of Archibald J. Turner, Serial No. 138,824, filed September 7, 1926.
- 55 This connecting means may consist in a plurality of parallel adjustable tension members covered by a flat casing as shown, or a single flat connecting member adjustable in length by buckling or tying.
- 60 The adjustable connecting means thus provided between the outer coverings of the thumb and forefinger, presenting a substantial area of flat surface between these digits, together with that portion of the integral palm piece covering the bases of the first and second fingers, comprise a catching area somewhat farther extended towards the tips of the fingers than is possible in the ordinary type of glove. The approximate area of this catching surface is indicated by the dotted outline of the ball 20 in Fig. 1, except that in actual practice the ball is forced farther in between thumb 21 and forefinger 25, the shape of these members being distorted to form a pouched catching area of which the connection 22 may or may not form a part, depending on how closely thumb 21 and forefinger 25 are held together, but it will be observed that by my invention a solid piece of leather is disposed between the first and second fingers for this catching surface, thereby greatly prolonging the life of the glove. My invention also possesses the advantage of providing a catching surface which will not permit of injury of the player's hand due to splitting the first and second fingers, and by my invention the act of catching a ball is made much more certain, because of the decrease of the possibility of a fumble through the first and second fingers. By providing my novel outer casing with a lining having fingers duly separated, I have provided this construction in a glove which has the same feel and fit as the gloves hitherto made.
- While I have illustrated and described the preferred formation of construction for carrying my invention into effect, this is capable of many modifications without departing from the spirit of the invention, and I do not wish to be limited to the precise details of the construction set forth, but desire to avail myself of all advantages within the scope of the appended claims.
- What I claim as new and desire to secure by Letters Patent of the United States is:
1. In a hand protecting covering, the combination of a lining having a plurality of digit casings loosely fitted to the hand, with an outer covering comprising a single casing for the lower part of the first two fingers, separate casings for the upper parts of said fingers, and separate casings for the rest of the digits.
  2. In a hand protecting covering, the combination of a lining having a plurality of digit casings loosely fitted to the hand, with an outer covering comprising a single casing for the lower part of the first two fingers, separate casings for the upper parts of said fingers, and separate casings for the rest of the digits, the front part of said outer covering comprising an integral piece.
  3. In a hand protecting covering, the combination of a lining having a plurality of digit casings loosely fitted to the hand, with an outer covering comprising an integral front piece having an outline extending inward to the palm between the third and fourth fingers, inward a lesser distance be-

tween the second and third fingers, and inward a still lesser distance between the first and second fingers, and means to cover the thumb and the backs of the fingers.

- 5 4. In a hand protecting covering, the combination of a lining having a plurality of digit casings loosely fitted to the hand, with an outer covering comprising a single casing for the lower part of the first two fingers, separate casings for the upper parts of said fingers, separate casings for the rest of the digits, and padding between said lining and outer covering.
- 10 5. In a hand protecting covering, the combination of a lining having a plurality of digit casings loosely fitted to the hand, with an outer covering comprising a front piece covering the front of the palm and fingers and the back of the first and little fingers, back pieces for the second and third fingers, forming a single casing covering the base of the first and second fingers, and separate casings for the tops of said fingers and for the balance of the fingers, and a separate thumb casing.
- 15 6. In a hand protecting covering, the com-

bination of a lining having a plurality of digit casings loosely fitted to the hand, with an outer covering comprising a front piece covering the front of the palm and fingers and the back of the first and little fingers, back pieces for the second and third fingers, forming a single casing covering the base of the first and second fingers, and separate casings for the tops of said fingers and for the balance of the fingers, a separate thumb casing, and a substantially flat joining means for said thumb and first finger casings.

30 7. In a hand protecting covering, a lining loosely conforming to the digits of the hand and covering the palm, and an outer casing comprising an integral front piece, back pieces for the second and third fingers, and a thumb casing, said front piece and back pieces being adapted to form a single casing for the base of the first and second fingers and a split casing for the upper ends of said fingers.

35 45 8. In witness whereof, I hereunto subscribe my name this 31st day of August, 1926.

ALBERT F. HILTENBEITEL.
